UNITED STATES PATENT OFFICE.

EDWARD E. PINKERTON, OF SIOUX CITY, IOWA.

DESIGN FOR A PAPER-BOX BLANK.

SPECIFICATION forming part of Design No. 31,214, dated July 11, 1899.

Application filed June 13, 1899. Serial No. 720,410. Term of patent 14 years.

To all whom it may concern:

Be it known that I, EDWARD E. PINKERTON, of Sioux City, in the county of Woodbury and State of Iowa, have invented and produced a new and original Design for a Paper-Box Blank, of which the following is a full, clear, and exact specification.

Reference is to be had to the accompanying drawing, forming a part of this specification, in which the figure is a plan view of a paper-box blank, showing my design.

The design in its entirety consists of a center piece A, flanked by the sides B B' and the ends C C', of which the sides appear with slots D transverse to the sides and the ends C C' appear each with divided tongues E E', extending sidewise along the edges of the

sides B B' to a length corresponding approximately to the width of said sides, the latter being marked off from the center piece by scores or creases F F', the ends C C' being marked off by scores G G' from the center piece A and the tongues E E' being marked off from their ends by scores H H'.

The leading feature of the design consists of the center piece, the slotted sides, and the ends having divided tongues.

I claim—

The design for a paper-box blank herein shown and described.

EDWARD E. PINKERTON.
